(57) **CLAIM**

The ornamental design of a step bumper receiver, as shown and described.

DESCRIPTION

FIG. 1 is a perspective view of the step bumper receiver of the present invention;

FIG. 2 is a rear elevational view thereof;

FIG. 3 is a left side elevational view thereof, the right side elevational view being a mirror image thereof;

FIG. 4 is a top plan view thereof;

FIG. 5 is a front elevational view thereof; and,

FIG. 6 is a bottom plan view thereof.

The broken line showing of environment is for illustrative purposes only and forms no part of the claimed design.
